UNITED STATES PATENT OFFICE.

FRED W. POPP AND SAMUEL B. CLARK, OF VALLEJO, CALIFORNIA.

GAME BOARD.

1,426,599.

Specification of Letters Patent. Patented Aug. 22, 1922.

Application filed March 10, 1921. Serial No. 451,226.

To all whom it may concern:

Be it known that we, FRED W. POPP and SAMUEL B. CLARK, citizens of the United States, residing at Vallejo, in the county of 5 Solano and State of California, have invented certain new and useful Improvements in Game Boards, of which the following is a specification.

This invention relates to game boards, and 10 it comprises a board having a centrally arranged crown portion, the edges of said crown portion being horizontal and provided with a groove extending substantially to the adjacent meeting edges, inclined surfaces arranged beyond said groove, a plurality of openings arranged in said surfaces, collecting troughs arranged beneath said openings, and means for propelling a sphere over said board.

20 In the present invention, we have provided a baseball game board, in which marbles are employed to represent the base runners, and means are provided for propelling the marbles over the board. The 25 rules of baseball in regard to put-outs and run scoring apply to the game, and a plurality of openings are provided on the surface of the board representing the different players in the field. When a marble falls 30 through one of these openings, it represents a put-out for the team in the field, and three outs represent an inning, as in the game of baseball. A home plate opening is provided, and a marble passing through this opening 35 represents a run for the team at bat.

The surface of the board adjacent the periphery is inclined inwardly, and a centrally arranged crown-shaped portion representing the baseball diamond is provided. 40 The outer surface is also inclined between each pair of bases, with the high points arranged intermediate the bases, and the bases at the lowest point on the board. The openings representing the base and the out-fielders are arranged in these low points so that 45 a marble or sphere, when propelled, will pass over one of the points to the next base, and if it has not sufficient momentum to pass over the high point, will return to the base which it has left. When the marble comes to rest at a point adjacent one of the corners of the diamond, it is in position to be propelled around the bases. If, instead of coming to rest on the surface of the 55 board, it drops through one of the openings, it represents a put-out.

In the accompanying drawings, we have shown one embodiment of the invention. In this showing:

Figure 1 is a plan view, 60

Figure 2 is a side elevation,

Figure 3 is a plan view of the board with the top removed, showing the propelling mechanism,

Figure 4 is a transverse vertical sectional view on line 4—4 of Figure 1,

Figure 5 is a similar view on line 5—5 of Figure 1,

Figure 6 is a transverse vertical sectional view on line 6—6 of Figure 1, 70

Figure 7 is a detail sectional view on line 7—7 of Figure 1,

Figure 8 is a perspective view of the propelling mechanism, and,

Figure 9 is a similar view of the sphere or 75 marble.

Referring to the drawings, the reference numeral 1 designates a pair of diagonally arranged supporting members which, as shown, are channel shaped in cross-section. The outside frame is supported in recesses 2, formed on the ends of the diagonal supporting members. As shown, the frame comprises a pair of members 3 and 4. The top 5 of the game board is adapted to be arranged between these members, and the side members are properly shaped to receive the top of the board. As shown in Figure 2 of the drawings, the bottom member 3 is enlarged near the center of each side, as at 6, 90 and the top member 4 is correspondingly recessed.

The board 5 comprises a raised center portion or crown 8, resembling a baseball diamond, the crown being provided with a plurality of flat grooves 9, extending outwardly from the center to each corner. The portion of the board outside the crown extends upwardly toward the edge, as at 10, whereby grooves 11 are provided on the four sides of 100 the crown communicating with the grooves 9, extending from the center of the crown. The portion 10 of the board is further inclined longitudinally to provide a high portion 12, intermediate the ends. Adjacent 105 each corner of the board, the outer space is flat, as at 13 (see Figures 5 and 6). The longitudinal incline from the point 12 terminates at a point slightly removed from the corner, as shown in Figure 2 of the drawings, and as the edge of the board is in the same plane with the outer end of the groove 110

9, there is no incline transversely of the board. The side pieces 4 are provided with cut-out portions to provide recesses 14, arranged in the corners of the board. In one 5 of these corners, an opening 15 is provided with suitable indicia, as at 16, to indicate the catcher's position. Diagonally in alignment with this opening is a second opening 17, arranged at the end of the groove to indicate 10 the pitcher's position. As shown, the pitcher's box is indicated at 18, near the center of the diamond, but the opening 17 is provided to permit the pitcher to score put-outs. The other three corners are provided 15 with openings 19, arranged in a position corresponding to the opening 17, and are provided with indicia to indicate first base, second base, and third base, respectively. The recesses 14 are provided with openings 20 20, 21, and 22, representing the right fielder, center fielder, and left fielder, respectively.

The flattened portions 13 of the board are provided with slots 23, arranged between the pair of openings in each of the flattened portions. A propelling device comprising four arms 24 is pivotally mounted in the supporting members 1 and 2 beneath the board, as at 25, and this member is provided with arms 26, projecting through the slots 23. 30 An operating member 27 is connected to the propelling member, as at 28, and is provided with an operating lever 29, projecting beyond the edge of the board adjacent the catcher's position. This arm is pivoted in 35 one of the side members, as at 30.

The surface of the board is further provided with suitable indicia, as at 31, to indicate the position of the short-stop between the second base and third base. The surface 40 of the board may be provided with additional raised portions 32 to vary the course of the sphere or marble. A home plate opening 33 is provided at the juncture of the inclined surface 10, between the third 45 base and the catcher's position and the flattened surface 13 in which the catcher's position is located. Beneath the board, a trough 34 is provided to receive marbles passing through the opening 33 and convey 50 them to the outside of the board.

Arranged beneath the surface of the board are a plurality of troughs to convey the spheres passing through the openings to a point of delivery adjacent the catcher's position. As shown, a trough 35 is arranged diagonally of the board extending from a point below the openings 19 and 21 to the other side of the board beneath the openings 15 and 17. The trough is inclined to convey 60 the spheres to the end beneath the catcher's position and communicates with the opening 36 in one of the side pieces to permit the spheres to pass out. A pair of troughs 37 are arranged at right angles to the trough 35, beneath the openings 19 and 20, at one

side of the board, and the openings 19 and 22 at the other side of the board. These troughs are inclined toward the center of the board and are adapted to discharge the spheres into the trough 35.

In Figure 9 of the drawings, one of the spheres or marbles 38 is shown. A suitable number of these spheres are provided to permit the game to be played and a batter provided at all times, regardless of the number 75 of men on the bases.

In operation, a sphere is placed in front of the arm 26, arranged adjacent the catcher's position and the operating lever 29 is swung on its pivot to operate the propelling 80 mechanism and drive the sphere. Due to the inclines 12, the sphere will eventually settle in one of the flattened portions 13. If a sphere driven from the catcher's position acquires sufficient momentum to travel up 85 the incline between the first base and second base, it will either pass over this incline and travel toward the flattened portions 13 at second base, or if its momentum is insufficient, to reach the top of the incline, it will 90 return to the first base. The length of the slot 23 and the distance between it and the pair of openings arranged in each flattened portion is such that the sphere will either 95 pass through one of the openings indicating a put-out or will come to rest at a point where it may be engaged by the arm 26 when the propelling member is operated. When the propelling member is operated, all of the arms 26 will move simultaneously and any 100 spheres on the board will be struck by the arms. The groove 11 serves to prevent the spheres from riding up on the center or crown portion of the board, but if the sphere should travel on the crown portion of the 105 board, it is unable to remain there as the crown portion is inclined in all directions from the center. The grooves 9 further serve to return the spheres to the flattened portions 13 where they will either come to 110 rest within the range of the arm 26 or pass through one of the openings in the board.

Any number of additional inclines 32 may be provided to vary the usual course of the game. It will be apparent that skill will 115 be required to drive a marble or sphere around the board without entering one of the put-out openings. Due to the position of the home plate opening 33, it will be further apparent that under different conditions, a different force should be applied to the operating lever 29 by a skillful operator. If a runner is on third base, it is more desirable to have him score than to have the batter reach first base, and the 120 operator will govern his action accordingly.

It is to be understood that the form of our invention herewith shown and described is to be taken as a preferred example of the same, and that various changes in the shape, 125 130

size, and arrangement of parts may be resorted to without departing from the spirit of our invention or the scope of the subjoined claims.

5 Having thus described our invention, we claim:

1. A base ball game board comprising a substantially rectangular portion formed of a plurality of inclined surfaces and a surrounding portion formed of a plurality of inclined surfaces, said board being provided with a pair of openings arranged adjacent each corner of the rectangular portion, the spaces between said pairs of openings being level to permit a sphere to remain thereon in a state of rest, and propelling devices adapted to simultaneously engage spheres located on said level portions.

2. A game board comprising a substantially rectangular portion formed of a plurality of inclined surfaces and a surrounding portion formed of a plurality of inclined surfaces, said board being provided with a pair of openings adjacent each corner of the rectangular portion, the space between said openings being level to permit a sphere to remain thereon in a state of rest, said level spaces being provided with slots, a propelling device projecting through each of said slots, and common operating means for said propelling device.

3. A game board comprising a raised central portion substantially rectangular in shape, a surrounding section comprising a plurality of inclined portions, said inclined portions being connected to each other by flattened portions, said flattened portions being provided with pairs of openings, and

a propelling device arranged adjacent each pair of openings.

4. A game board comprising a raised central portion substantially rectangular in shape, a surrounding section comprising a plurality of inclined portions and flattened portions, each of said flattened portions being provided with a pair of openings, a propelling device arranged adjacent each pair of openings, and common operating means for said propelling devices.

5. A game board comprising a raised central portion substantially rectangular in shape, a surrounding section comprising a plurality of inclined portions and flattened portions, said flattened portions being provided with pairs of openings, a propelling device arranged adjacent each pair of openings, and a collecting trough arranged beneath said board in alinement with said openings.

6. A game board comprising a raised central portion substantially rectangular in shape, a surrounding section comprising a plurality of inclined portions and flattened portions, each of said flattened portions being provided with a plurality of openings, a propelling device arranged on each of said flattened portions, common operating means for said propelling devices, and collecting troughs arranged below said openings.

In testimony whereof we affix our signatures in presence of two witnesses.

FRED W. POPP.
